UNITED STATES PATENT OFFICE.

PHILIP N. CURTIS, OF WORCESTER, MASSACHUSETTS, ASSIGNOR TO BAKER BOX COMPANY, OF WORCESTER, MASSACHUSETTS, A CORPORATION OF MASSACHUSETTS.

REINFORCED PACKING BOX.

Application filed September 19, 1924. Serial No. 738,692.

To all whom it may concern:

Be it known that I, PHILIP N. CURTIS, a citizen of the United States, residing at Worcester, in the county of Worcester and 5 State of Massachusetts, have invented a new and useful Reinforced Packing Box, of which the following is a specification.

This invention relates to a packing box reinforced with metal banding and has for 10 its general object the provision of a box having a new and novel arrangement and disposition of metal banding from which construction important and improved results are obtained. With my new construction, a 15 box of greatly increased strength is produced, while at the same time the thickness of the lumber used may be materially reduced. My improved box is also much more difficult to open and tends greatly to dis- 20 courage and reduce theft during transit.

A preferred form of my invention and a modification thereof are shown in the drawings in which

Fig. 1 is a perspective view of my im- 25 proved box with the cover spaced therefrom;

Fig. 2 is an end view thereof with the cover secured;

Fig. 3 is a detail sectional view, taken 30 along the line 3—3 in Fig. 2; and

Fig. 4 is a partial view of a modification.

Referring to the drawings, my improved box is formed with end members 10, sides 11, a bottom 12, and a top 13, the bottom 35 and top being collectively designated herein as covers. These several parts of the box may be made of any suitable material, wood being commonly used. In the form of my invention shown in Figs. 1 to 3, the sides 11 and covers 12 and 13 are provided with slots 14 extending cross-wise of the end portions thereof, these slots being adapted to receive four pieces of metal strap or banding 15, 16, 40 17 and 18 at each end of the box.

In the preferred construction, the pieces 45 of banding or strapping 15 and 16 are inserted in slots 14 of the sides 11 and the sides 11 are then secured to the ends 10 by fastening members 20. The ends of the 50 straps 15 and 16 are then bent closely about the corners of the box ends 10, as clearly shown in Figs. 1 and 2, and the covers 12 and 13 are then attached to complete the 55 box.

The ends of the straps 17 and 18 are bent

to overlap the sides 11, and additional fastening members 21 (Fig. 2) are provided to secure the sides and covers to the box. Each of these fastening members 21 at the corners of the box extends through two overlapping pieces of strap or banding at each side of each corner of the box. The corners are thus double bound and it is also found that the fastening members 21 extending through two pieces of banding are much more firmly held in the box and have a much greater resistance to withdrawal.

It has been found by actual test that a box thus constructed will safely receive a much greater weight of material and that it will resist rough usage more successfully than a box of the usual construction having twice the thickness of lumber. This decrease in the thickness of the lumber not only reduces the cost of the material entering into the box but also reduces the weight thereof with a corresponding reduction in freight charges.

For some purposes, the permissible reduction in thickness of lumber leaves the 80 sides and covers so thin that the slots 14 are not advisable. Under these circumstances, the construction shown in Fig. 4 is desirable, in which the straps 30 and 31 are placed outside of the sides 32 and the covers 33 instead of being placed in slots in the ends thereof. The straps 30 are overlapped around the end members 34 and the straps 31 are overlapped around the sides 32 and the straps 30. The fastening devices 35 at 90 the corners each extend through two pieces of strap or banding at each side of each corner as in the form previously described.

It will be understood that the projecting portions of the straps are not limited to 95 any particular length and that they may extend any desired distance across the adjacent sides or ends of the box.

Having thus described my invention and the advantages thereof, I do not wish to be 100 limited to the details herein disclosed otherwise than as set forth in the claims, but what I claim is:

1. A packing box comprising ends, sides and covers, said sides and covers being each 105 provided with separate pieces of metal banding extending crosswise in slots extending inwardly from the end edges thereof, said pieces of banding having portions projecting beyond the longitudinal edges of said sides 110

and covers and said projecting portions overlapping other pieces of banding adjacent the corners of said box, with certain of said projecting portions spaced from said other 5 pieces of banding by a portion of box material, and fastening members extending through two overlapping pieces of banding at each side of each corner of said box and through the intervening box material and 10 into a box member to firmly secure said box together, the end members being enclosed by the sides and cover.

2. A packing box comprising ends, sides and covers, said sides and covers being slotted inwardly from the end portions thereof, and a separate piece of metal banding inserted edgewise in the slot in each side and cover, the projecting end portions of the banding for the sides overlapping and 15 directly engaging the adjacent portions of the box ends and the projecting end portions of the banding for the covers overlapping and directly engaging the outer surface of adjacent portions of the sides, and fastening 20 members extending through said overlapping bands and through an intervening portion of box material, and firmly securing said box together, said sides and covers enclosing the ends.

3. In a packing box, ends for said box, sides for said box each provided with separate pieces of metal banding extending crosswise in slots extending inwardly from the end edges thereof and having portions 35 projecting substantially inward therefrom

and directly engaging the top and bottom edges of said ends, a bottom for said box also having a separate piece of metal banding extending crosswise at each end thereof and having projecting portions extending 40 upward along and directly engaging the outer surfaces of the sides but spaced from the side banding by a portion of box material, said bottom enclosing the lower edge of the end portion, said pieces of banding 45 overlapping each other at the lower box corners, and fastening members extending through portions of two adjacent pieces of banding and through said intervening box material and into said sides and bottom to 50 firmly secure said parts together.

4. A packing box comprising ends, sides and covers, said box being provided with metal banding having portions extending crosswise in slots extending inwardly from the end edges of said sides and covers, and fastening devices effective to secure said sides and covers to said ends, certain of said fastening devices extending through a portion of banding in one of said cover slots and 55 through the intervening box material between said slot and the associated end and through a second portion of banding between said cover and said end and into said end, thereby firmly securing said cover to 60 said end.

In testimony whereof I have hereunto affixed my signature.

PHILIP N. CURTIS.
